UNITED STATES PATENT OFFICE.

GEORGE HENRY WHEARY, OF RACINE, WISCONSIN.

COMBINATION TRUNK-SECTION COVER AND LAUNDRY-BAG.

1,387,221.

Specification of Letters Patent.

Patented Aug. 9, 1921.

Application filed May 13, 1920. Serial No. 381,058.

To all whom it may concern:

Be it known that I, GEORGE HENRY WHEARY, a citizen of the United States, and resident of Racine, in the county of Racine 5 and State of Wisconsin, have invented new and useful Improvements in Combination Trunk-Section Covers and Laundry-Bags, of which the following is a description, reference being had to the accompanying drawings, which are a part of this specification.

This invention relates to improvements in combination trunk section cover and laundry bag.

Wardrobe trunks of the present day are 15 divided medially of their length and extend vertically to form a wardrobe section and a drawer section. The wardrobe section is usually provided with a shoe box in its lower front portion and garment hangers in its upper portion for suspending garments thereon. The trunk sections are swung horizontally to open position and while containing garments usually remain in open position. While in open position no provision is made 25 for protecting the garments with the result that they become dusty and soiled in a short time.

Furthermore, means are not provided in the ordinary wardrobe trunk for taking care 30 of soiled linen with the result that it is usually placed in different portions of the trunk in a very unsanitary manner.

It is one of the objects of the present invention to overcome the before mentioned 35 objectionable feature and provide a combination trunk section cover and laundry bag which serves to cover and protect the garments suspended in the wardrobe section and which will also hold soiled linen and 40 keep it separate from the other articles of wear.

A further object of the present invention is to provide a combination trunk section 45 cover and laundry bag which may be easily secured to or removed from the trunk section when desired.

A further object of the invention is to provide a combination trunk section cover and laundry bag which may be easily attached to ordinary wardrobe trunks now on the market.

A further object of the invention is to provide a combination trunk section cover and laundry bag in which portions may be easily 55 removed from the trunk section and its supporting means for cleaning.

A further object of the invention is to

provide a combination trunk section cover and laundry bag which is of simple construction, is strong and durable, and is well 60 adapted for the purpose described.

With the above and other objects in view, the invention consists of the improved combination trunk section cover and laundry bag and its parts and combinations as set 65 forth in the claims, and all equivalents thereof.

In the accompanying drawing in which the same reference characters indicate the same parts in all of the views:

Figure 1 is a front view of the wardrobe section of a trunk showing the improved combination section cover and laundry bag mounted thereon, the view also indicating by dotted lines a portion of the other section of 75 the trunk;

Fig. 2 is a vertical sectional view of the front portion of the wardrobe section taken on line 2—2 of Fig. 1, taken on a larger scale; and

Fig. 3 is a transverse sectional view taken on line 3—3 of Fig. 1.

Referring to the drawing the numeral 5 indicates the wardrobe section of a wardrobe trunk, 6 the drawer section and 7 the 85 top portion of the said section which may be in the form of a hinged top cover or may be non-movably connected thereto. The wardrobe section is provided with upper parallel tracks 8 (only one being shown) upon which 90 are mounted garment hangers 9 for supporting garments thereon. An outwardly swingable shoe box 10 is mounted in the front lower portion of the wardrobe section and is normally maintained in upright position as 95 shown in Figs. 1 and 2.

The improved cover and laundry bag 11 comprises a piece of material, such as fabric, which is adapted to be suspended in front of the wardrobe section from the front edge 100 of the top 7 to the upper forward portion of the shoe box 10. The said cover is formed of a single piece of fabric folded and sewed to form an upper looped supporting portion 12, a lower attaching portion 13, a medial laundry bag portion 14 and an overlapped entrance opening 15 to the laundry bag, said opening being closed by snap buttons 16. The looped portion 12 is open at opposite ends and its upper part is provided with 105 openings 17 through which removably extend hooks 18. These hooks are fastened at their lower ends to a transverse supporting bar 19 loosely and removably extending into

the looped portion 12. In removing the bar, the hooks are slipped through the openings and the bar is slid lengthwise from the looped portion to permit cleaning the fabric.

5 The front lower edge of the top 7 is provided with inwardly and downwardly extending openings 20 to receive the hooks 18 and support the cover 11 therefrom.

The attaching portion 13 has a snap button engagement 21 with the upper front portion of the shoe box 5 which in connection with the upper hooked bar 18 holds the front portion of the cover in taut position over the entire exposed portion of the wardrobe section and keeps out the dust therefrom.

10 The rear or inner portion of the bag 14 is formed with a plait 22 to permit said portion to expand inwardly into the wardrobe space above the shoe box when soiled garments are placed therein.

15 In order to reinforce the front or outer side of the cover or bag, the front portion is plaited medially, transversely as indicated by the numeral 23 to form three thicknesses of material.

20 The front opening 15 permits easy access to the laundry bag without removal from the trunk section and when it is desired to 30 replace or remove apparel from the wardrobe section, it is only necessary to swing the cover over the top of the trunk or disengage the hooks from the top.

25 It will be noted that as the apparel is removed from the hangers and used and soiled and placed within the bag more room is provided in the wardrobe section to accommodate the increasing amount of apparel in the bag.

30 From the foregoing description, it will be seen that the combination trunk section cover and laundry bag is of very simple construction and is well adapted for the purpose described.

40 45 What I claim as my invention is:

1. The combination with a trunk wardrobe section having an open front and a shoe box mounted in its lower portion and closing a part of said open front, of a combined 50 cover and laundry bag for the remaining portion of the open front, comprising a double thickness of flexible material covering said open portion and having its inner thickness expandable inwardly into the said 55 trunk section, the outer thickness of material provided with an opening, a bar engaging the upper portion of the material and having means which removably engage the upper front portion of the trunk section, 60 and means releasably connecting the lower portion of the flexible material to the upper portion of the shoe box.

65 2. The combination with a trunk wardrobe section having an open front and a shoe box mounted in its lower portion and clos-

ing a part of said open front, of a combined cover and laundry bag for the remaining portion of the open front, comprising a piece of flexible material folded over upon itself to form a looped upper portion and a lower 70 securing portion and an inwardly expansible bag portion therebetween, the opposite ends of the material overlapping each other at the front to form an opening to the bag portion, a bar removably positioned in the looped portion and having hooks which extend through the material and removably engage upper front edge portions of the wardrobe section, and means removably connecting the securing portion of the flexible material to the 80 upper part of the shoe box.

3. The combination with a trunk wardrobe section having an open front and a shoe box mounted in its lower portion and closing a part of said open front, of a combined cover 85 and laundry bag for the remaining portion of the open front, comprising a piece of flexible material folded over upon itself to form a looped upper portion and a lower securing portion and an inwardly expansible bag portion therebetween, the opposite ends of the material overlapping each other at the front to form an opening to the bag portion closed by snap buttons, the looped portion of the material having openings formed in its upper portion, a bar removably positioned in the looped portion and having hooks which extend through the upper openings of the material and removably engage upper front edge portions of the wardrobe section, and 95 means removably connecting the securing portion of the flexible material to the upper part of the shoe box.

4. The combination with a trunk wardrobe section having an open front and a shoe 100 box mounted in its lower front portion and closing a part of said open front, the upper front edge portion of said section having openings formed therein, of a combined 105 cover and laundry bag for the remaining portion of the open front, comprising a piece of flexible material folded over upon itself to form a looped upper portion and a lower securing portion and an inwardly expansible bag portion therebetween, the opposite ends of the material overlapping each other and connected together by snap buttons to form a closable opening to the bag portion, the looped portion of the material having openings formed in its upper portion, a bar removably positioned in the looped portion and having hooks which extend through the upper openings of the looped portions and removably entering the 115 openings of the upper front edge portion of the section, and snap buttons connecting the lower securing portion to the upper portion 120 of the shoe box.

In testimony whereof, I affix my signature:
GEORGE HENRY WHEARY.
